(57) **CLAIM**

The ornamental design for a magnetic resonance tomography apparatus, as shown and described.

DESCRIPTION

FIG. 1 is an isometric perspective view of an embodiment of a magnetic resonance tomography apparatus, showing our new design;

FIG. 2 is a front elevation view of the magnetic resonance tomography apparatus shown in FIG. 1;

FIG. 3 is a rear elevation view of the magnetic resonance tomography apparatus shown in FIG. 1;

FIG. 4 is a top plan view of the magnetic resonance tomography apparatus shown in FIG. 1;

FIG. 5 is a bottom plan view of the magnetic resonance tomography apparatus shown in FIG. 1;

FIG. 6 is right elevation view of the magnetic resonance tomography apparatus shown in FIG. 1; and,

FIG. 7 is left elevation view of the magnetic resonance tomography apparatus shown in FIG. 1.

The broken lines in the drawings are included for the purpose of illustrating portions of the magnetic resonance tomography apparatus that form no part of the claimed design.
